UNITED STATES PATENT OFFICE.

ROBERT GANS, OF NEW YORK, N. Y.

PENCIL-SHARPENING DEVICE.

1,234,652.

Specification of Letters Patent. Patented July 24, 1917.

Application filed March 29, 1917. Serial No. 158,161.

To all whom it may concern:

Be it known that I, ROBERT GANS, a citizen of the United States, and a resident of the borough of Manhattan, city, county, and 5 State of New York, have invented certain new and useful Improvements in Pencil-Sharpening Devices, of which the following is a specification.

My improvements relate to the class of 10 pencil sharpeners in which the pencil is rotated in its longitudinal axis while subjected to the action of the cutting blades; and my object is to afford a simple, cheap yet effective and substantial structure adapted to the 15 requirements of general use,—the invention consisting in the specific construction and arrangement of parts described and claimed; and the distinctive features being the formation of several parts in one piece with the 20 standard plate; the cutter disk with blades and chuck-gear-actuating lugs integral therewith; and the peculiar formation of the rotatable pencil chuck, all as hereinafter fully set forth.

25 In the accompanying drawings,

Figure 1, is a front view of my improved pencil sharpening device;

Fig. 2, is a rear view thereof;

30 Fig. 3, is a top view thereof;

Fig. 4, is a side elevation thereof;

Fig. 5, is a horizontal sectional elevation taken upon plane of line 5—5, Fig. 1;

Fig. 6, is an elevation of the hub piece.

Fig. 6^a, is an end view thereof.

35 Fig. 7, is a vertical sectional elevation taken upon plane of line 7—7, Fig. 1;

Fig. 8, is a view of the standard plate blank before folding into shape;

Fig. 9, is a view of the inner or rear side 40 of the cutter disk;

Fig. 10, is a sectional elevation of the pencil rotating chuck and adjacent parts, taken upon plane of line 10—10, Fig. 2;

Fig. 11, is an end view of the clutch gear.

45 Fig. 11^a, is an end elevation of its sleeve.

Fig. 11^b, is a side view thereof.

Fig. 12, is an end elevation of the spring bushing.

Fig. 12^a, is a side view thereof.

50 The basic structure is the standard plate A, formed of suitable sheet metal shaped by dies in a manner well known in the arts. The blank of this standard plate A, is shown in Fig. 8, before certain parts of it are bent over into operative position. Thus the triangular side extensions a, a, of the main

plate or standard A, are folded over at substantially right angles thereto to form abutments which sustain the said main plate A, rigidly and reinforce it against the strain of use,—the feet a', a', a', being also bent over at right angles to the standard A, and formed with holes to facilitate attachment to a suitable base by means of screws or other securing devices. The wing a², is formed 60 with the conoidal concavity a³, which constitutes the pocket for the support of the end of the pencil to be sharpened,—said wing a², being bent over against the rear side of the standard A, with its said conoidal concavity a³, in axial alinement with that of the center of the aperture a⁴, which extends through the standard plate and forms with the concavo-conoidal pocket a³, the lower part of the cavity a³ being indented, as 70 shown at a⁴⁰ so as to be readily inserted in the apex of the opening a⁴, the matrix in which the end of the pencil is rotated while subjected to the action of the cutting blades d, on the rotatable disk D.

80 a⁵, is the horizontal slot through which the teeth of the chuck gear e, protrude; and a⁶, a⁶, are vertical slots through which the hook-lugs s, s, of the shavings cup or receptacle S, protrude,—the said hook-lugs 85 s, s, engaging with the lower end walls of said slots a⁶, a⁶. a⁷, a⁷, represent rivet holes, and a⁸, a⁸, inturned rivet studs upset from the standard plate A, and to be used in lieu of extraneous rivets or similar attaching devices in securing the adjunctive parts rigidly to the standard. a⁹, a⁹, are spacing lugs upset from the plate A, for the lateral support and alinement of the inner face of the cutter disk D, when the latter is mounted in position on the standard A; and the extension a¹⁰, is bent over the face of the standard plate A, to laterally support and aline the outer face of said disk D,—the spacing lugs a⁹, a⁹, and this bearing arm a¹⁰, acting in conjunction to limit and prescribe the plane of rotation of said cutting disk D,—both the bearing arm a¹⁰, and the lugs a⁹, a⁹, being rigid, so as to positively prevent lateral deflection of the disk D, and hold the cutting 100 blades true to their work.

The chuck member C, is mounted in a bearing B, attached to the rear face of the standard plate A, at an angle with relation thereto, the side flanges b, b, of said bearing 110 being preferably secured to the plate A, by means of rivet studs a⁸, a⁸, upset from the

plate as before stated. The axis of the clutch member C, coincides with that of the matrix a^3 , a^4 , below; and the inclination of these axes from the plane of the standard plate A, is equivalent to that of the conoidal "point" to be imparted to the pencil. The inner wall of the concavo-conoidal pocket a^3 , extends down to the inverted apex or acute angle of the aperture a^4 , thus affording ample, secure and uniform support for the exposed central core of plumbago and reinforcing and sustaining the same against the thrust of the cutting blades, so that if said graphite core is of fairly good quality there will be no danger of breakage or rupture thereof during the sharpening operation. In other words a continuous, unbroken support is afforded to the end of the pencil point by the pocket a^3 , as opposed to the action of the cutting blades, so that the exposed graphite core is effectually reinforced and sustained against the strain involved in reduction by the cutting blades. In order to attain this result the floor of the pocket a^3 , is extended through the aperture to the front surface of the standard plate A, as shown in Figs. 5, and 10.

The rotatable chuck member C, consists of the spur wheel or gear c , the gear hub or sleeve c' , and the spring bushing c^2 . The gear c , is recessed as at c^x , to receive radial lugs c'' , on the upper end of the sleeve c' , and the latter is in turn recessed, as at c''' , to receive radial lugs c^{22} , on the upper end of the spring bushing c^2 . The recesses c^x , c''' , and the lugs c'' , c^{22} , are preferably of dove-tail shape, and the lugs are peened tightly within the recesses, so as to afford a permanent connection. By this means the parts of the rotor C, may be rigidly secured together in a simple, cheap and effective manner. The lower extremity of the bushing c^2 , extends below the sleeve c' , and is split into a series of bent spring jaws c^{23} , which grip the pencil firmly so that it will rotate with the clutch against the resistance afforded by the cutting blades.

The rotatable cutting disk D, is formed of a single piece of suitable sheet metal stamped into shape with a plurality of equidistant tangential blades d , d , upset therefrom, three of these blades being shown in the drawings. The protuberant inner edges of these blades are sharpened to form cutting edges which trim the end of a pencil inserted in the matrix a^3 , a^4 . The disk is also formed with the upset and inturned spurs or lugs d' , d' , which, when the disk is rotated, contact successively with the teeth of the chuck gear c , to rotate the chuck. Three of these chuck gear actuating lugs d' , are shown in the drawings as positioned, relatively as to direction of motion, behind the cutting blades, so as to turn the chuck and pencil slightly between each cut to present

fresh surfaces of pencil to the blades successively. The blades d , d , acting at an angle as related to the axis of the matrix a^3 , a^4 , tend constantly in action to draw the pencil downward farther into the matrix, rendering the device self-feeding to a certain extent, until the perfected point fits and rests in the inverted apex of the matrix, when the cutting edges cease to reach and reduce the pencil "point." 75

The cutter disk D, is provided with a suitable handle d^2 , and it is mounted upon an axis e' , forming part of the central bearing piece e , which is also formed with an annular shoulder e^2 , which fits into the annular opening a'' , formed for it in the standard A. The main flange of the center piece e , acts as a washer to space the cutter disk D, apart from said standard; and the axis e' , is slightly greater in width than the thickness of the disk D, so that the latter may rotate freely thereon. The central bearing piece e , is hollow to admit the shank of a screw stud i , the threaded end of which engages with a nut i' , at the rear of the plate, 90 thereby binding the said bearing piece e , firmly in position on the standard A, without interfering with the rotation of the cutter disk D, since while the head of the screw confines the disk D, to its axis e' it 95 does not impede its rotation because the width of the latter is slightly greater than the thickness of the disk D, as before stated. Thus, also, the cutter disk D, is free to conform to the alinement prescribed by the 100 spacing lugs a^9 , a^9 , and bearing arm a^{10} , as hereinbefore set forth.

f , is a ratchet spring which tends constantly to hold the clutch member C, against rotation, while yielding to the actuating 105 lugs d' , on the cutter disk D.

By the use of rivet lugs upset from the body of the standard plate A, and peened into holes formed for them in the attached parts as hereinbefore indicated, I am enabled not only to effect great economy in manufacture but also to produce a strong, substantial, rigid structure well adapted to withstand the strain to which the parts are subjected during use. Likewise the making 110 of the pencil pocket or conoidal concavity a^3 , and the bearing arm a^{10} , in one piece with the standard A, is another economical feature; as is also the formation of the cutting blades d , and gear-actuating lugs d' , in one 120 piece with the disk D.

The structure of the rotatable clutch member C, is also simple and inexpensive, the interlocking of the parts as set forth materially reducing the cost of manufacture. 125

What I claim as my invention and desire to secure by Letters Patent is,

1. In a pencil sharpening device of the character designated, a sheet metal standard plate formed with a lateral extension bent 130

over and secured to the main plate, said extension being formed with a conoidal concavity coinciding axially with an aperture in the plate, said aperture and said conoidal concavity constituting the matrix for the pencil, for the purpose set forth.

2. In a pencil sharpening device of the character designated, a sheet metal standard plate formed with a lateral extension 10 bent over and secured to the main plate, said extension being formed with a conoidal concavity coinciding axially with an aperture in the plate, said aperture and said conoidal concavity constituting the matrix 15 for the pencil, and a rotatable cutting disk mounted in spaced relation to said plate with its blades operable adjacent said concavity.

3. A blank for a pencil sharpening device, the same consisting of a plate having an 20 aperture and a wing with a conoidal concavity, said wing being foldable upon the plate to bring the concavity and the aperture coincident, said plate having a lateral extension to form a bearing arm and triangular 25 side extensions and bendable portions to constitute feet.

4. A blank for a pencil sharpening device, the same consisting of a plate having an aperture and a wing with a conoidal concavity, said wing being foldable upon the 30 plate to bring the concavity and the aperture coincident, said plate having a lateral extension to form a bearing arm and triangular side extensions and bendable portions to constitute feet, said plate being formed with spacing lugs acting in conjunction with said bearing arm to limit and prescribe the plane 35 of rotation of a cutting disk.

5. A blank for a pencil sharpening device, 40 the same consisting of a plate having an aperture and a wing with a conoidal concavity, said wing being foldable upon the plate

to bring the concavity and the aperture coincident, said plate having a lateral extension to form a bearing arm and triangular side 45 extensions and bendable portions to constitute feet, said plate being formed with spacing lugs acting in conjunction with said bearing arm to limit and prescribe the plane of rotation of a cutting disk, said 50 plate being further formed with a slot for the reception of the teeth of a gear.

6. A blank for a pencil sharpening device, the same consisting of a plate having an aperture and a wing with a conoidal concavity, said wing being foldable upon the 55 plate to bring the concavity and the aperture coincident, said plate having a lateral extension to form a bearing arm and triangular side extensions and bendable portions to constitute feet, said plate being formed with spacing lugs acting in conjunction with said bearing arm to limit and prescribe the plane of rotation of a cutting disk, said plate being further formed with a slot for the reception 60 of the teeth of a gear and with slots for the attachment of a shaving receptacle.

7. In a pencil sharpening device of the character designated, a pencil matrix comprising a part formed with a conoidal concavity, and a standard plate formed with an aperture having convergent sides and axially coincident with the said conoidal concavity, the floor of which extends through said aperture in the standard to the front 70 surface of the latter, together with a rotatable disk having cutter blades in the path of which said aperture is positioned, for the 75 purpose described.
